PISTON EXPANDER

Leon A. Witter, Cleveland, Ohio

Application September 3, 1932, Serial No. 631,610

12 Claims.

(Cl. 309—12)

This invention relates to means for expanding the split skirt of a piston. The invention contemplates the skirt as being of relatively soft metal such as an alloy of aluminum, and the 5 principal object of the invention is to provide expanding means readily attachable to any piston of such description, and attachable if necessary, without removal of the piston from its cylinder.

10 A further object of the invention is to provide that the expanding effect be applied to the piston in the zone of the wrist pin, and be adjustable in amount and yielding in character.

The exact nature of this invention together 15 with further objects and advantages thereof will be apparent from the following description taken in connection with the accompanying drawing, in which Figs. 1 and 2 are generally longitudinal sections through a typical piston 20 illustrating an embodiment of my invention applied thereto, the section of Fig. 1 being as in the plane of the wrist pin and the section of Fig. 2 being as indicated line 2—2, Fig. 1, and generally in the plane transverse of the wrist 25 pin; Figs. 3 and 4 are transverse sections as in the planes of lines 3—3 and 4—4 respectively, Figs. 1 and 2.

With reference now to the drawing, the piston shown is of conventional inexpensive design 30 for light alloys. The principal parts of the piston are the usual head 1 having ring grooves 2, wrist pin bosses 3, having aligned openings 4 for a wrist pin, and a skirt 5 joined with the wrist pin bosses. The parts are integral but the skirt 35 5 is separated from the head part of the piston by transverse slots 6 and on one side of the wrist pin bosses the skirt is split generally longitudinally as at 7.

It is the intent that the skirt be yieldably 40 expanded to fit the cylinder in which the piston moves, as after wear upon the piston and/or its corresponding cylinder wall, or after fatigue of the split part of the piston skirt; and my invention provides auxiliary means attachable to expand the piston skirt under these conditions.

The principal parts of the invention are a pair of bow members 8 and 9 and means for interassociating the medial parts thereof.

The bow member 8 has its ends 10 enlarged 50 as indicated and recessed as at 11 to seat upon the inwardly projecting parts of the wrist pin bosses 3, with the bow member extending laterally from the bosses toward the split side of the piston.

55 The bow member 9 is longitudinally disposed,

in straddling relation with the transverse bow member 8. Its end parts 12 are wide enough to bridge the split 7 of the skirt and are shaped as indicated Fig. 2 so that one may seat in the slot 6 which separates the skirt and head parts of the piston, at the end of the split 7. Preferably both ends 12 are similarly formed so that either may seat in the slot 6 and thus position the longitudinal bow member substantially positively against the piston wall.

10 One or both of the bow members are of resilient material such as spring steel, and both are preferably of sheet metal and thus inexpensive.

The medial parts of the bow members have 15 openings to receive a bolt 13 having a nut 14 by which the bows may be pulled together. The bow member 9 may have grooves 15 to receive 20 projections 16 on the nut 14 whereby the nut will be retained in its adjusted positions. The head end 17 of the bolt is preferably a press fit 25 in the bow member 8 so that the bolt will not turn as its nut is being adjusted.

Operation will be apparent. When the device 30 is to be applied to a piston the nut 14 is loosened and the parts inserted to the positions indicated, the transverse bow member seating against the wrist pin bosses and the longitudinal bow member being positioned by the seating of its inner end 12 in the slot 6 of the piston. The nut 14 is then turned down to bring the medial parts of the bow members together. This 35 springs the bow members, putting them under tension to exert pressure outwardly against the split side of the piston skirt. As the bow member 9 is sprung its lower end may move slightly downwardly along the piston wall. When the skirt part of the piston is thus brought up to the desired diameter the parts are 40 securely engaged with the piston and the setting of the nut 14 is maintained by the projections 16 thereon engaging the slots 15. The piston skirt is then of proper diameter but is still contractable against the yielding tension of the 45 expanding device.

It will be noted that the device may be applied and adjusted without disturbing a wrist pin which may be mounted in the bosses 3 or a connecting rod mounted on said wrist pin. In fact the device may be applied and adjusted 50 without removing a piston from its cylinder.

What I claim is:

1. Means for expanding a piston having a pair of wrist pin bosses and a split skirt, said means comprising a pair of bow members one seating at its ends upon the wrist pin bosses of 55

the piston and extending laterally therefrom toward the split side of the piston, the other extending within said piston longitudinally thereof with its ends bridging the split of the piston skirt, and means interassociating the medial parts of said bow members to exert outward pressure from said bosses to said skirt.

2. Means for expanding a piston having a pair of wrist pin bosses and a split skirt, said means comprising a pair of bow members one seating at its ends upon the wrist pin bosses of the piston and extending laterally therefrom toward the split side of the piston, the other extending within said piston longitudinally thereof with its ends bridging the split of the piston skirt, and means interassociating the medial parts of said bow members to exert outward pressure from said bosses to said skirt, one of said bow members being of spring material whereby said pressure will have a yielding characteristic.

3. Means for expanding a piston having a pair of wrist pin bosses and a split skirt, said means comprising a pair of bow members one seating at its ends upon the wrist pin bosses of the piston and extending laterally therefrom toward the split side of the piston, the other extending within said piston longitudinally thereof with its ends bridging the split of the piston skirt, and means interassociating the medial parts of said bow members to exert outward pressure from said bosses to said skirt, said bow members being of spring material whereby said pressure will have a yielding characteristic.

4. Means for expanding a piston having a pair of wrist pin bosses and a split skirt, said means comprising a pair of bow members one seating at its ends upon the wrist pin bosses of the piston and extending laterally therefrom toward the split side of the piston, the other extending within said piston longitudinally thereof with its ends bridging the split of the piston skirt, and means for adjustably interassociating the medial parts of said bow members to exert variable outward pressure from said bosses to said skirt.

5. Means for expanding a piston having a pair of wrist pin bosses and a split skirt, said means comprising a pair of bow members one seating at its ends upon the wrist pin bosses of the piston and extending laterally therefrom toward the split side of the piston, the other extending within said piston longitudinally thereof with its ends bridging the split of the piston skirt, said bow members arranged each straddling the other, and bolt means connecting their medial parts, whereby tightening of said bolt

means will produce outward pressure from said bosses to said skirt.

6. Means for expanding a piston having a pair of wrist pin bosses and a split skirt, said means comprising a transverse bow member having its ends recessed and seating upon the wrist pin bosses of the piston, with a medial part extending laterally therefrom toward the split side of the piston, a longitudinal bow member having its ends bridging the split of the piston skirt and with a medial part extending inwardly thereof, and means interassociating the medial parts of said bow members.

7. Means for expanding a piston having a pair of wrist pin bosses and a split skirt, said means comprising a transverse bow member having its ends recessed and seating upon the wrist pin bosses of the piston, with a medial part extending laterally therefrom toward the split side of the piston, a longitudinal bow member having its ends bridging the split of the piston skirt and with a medial part extending inwardly thereof, said bow members being arranged each straddling the other, and means connecting their medial parts and adapted to adjustably pull them together.

8. Means for expanding a piston having a pair of wrist pin bosses and a split skirt, said means comprising a transverse bow member having its ends seating upon the wrist pin bosses of the piston, with a medial part extending laterally therefrom toward the split side of the piston, a longitudinal bow member having its ends bridging the split of the piston skirt, with one end seated in the slot at the end of said skirt, with a medial part extending inwardly, and means connecting the medial parts of said bow members.

9. Means for expanding a piston comprising a pair of bow members arranged in cruciform relation, and means interassociating their medial parts.

10. Means for expanding a piston comprising a pair of bow members arranged in cruciform relation, and means interassociating their medial parts, one of said bow members being of spring material.

11. Means for expanding a piston comprising a pair of bow members arranged in cruciform relation, and means interassociating their medial parts, said bow members being of spring material.

12. Means for expanding a piston comprising a pair of bow members arranged in cruciform relation, and means for adjustably interassociating their medial parts.

LEON A. WITTER.
